DEVICE FOR SQUEEZING AND STORING COLLAPSIBLE TUBES
COMPRISING A HOLLOW CASING WITH ROLLERS THEREIN

Filed March 12, 1948

UNITED STATES PATENT OFFICE

2,566,503

DEVICE FOR SQUEEZING AND STORING
COLLAPSIBLE TUBES COMPRISING A
HOLLOW CASING WITH ROLLERS
THEREIN

George H. Snyder, Toledo, Ohio

Application March 12, 1948, Serial No. 14,464

3 Claims. (Cl. 222—102)

1

My invention relates to a device for holding and compressing a flexible tube, for containing shaving cream, tooth paste or other plastic material.

An important object of the invention is to provide a device of the above mentioned character, which is easy to operate and relatively simple and compact.

A further object of the invention is to provide a device of the above mentioned class, wherein the empty portion of the flexible tube may be stored within the device.

A still further object is to provide a device of the above mentioned class, designed to facilitate the easy removal of empty tubes therefrom.

Other objects and advantages of the invention will be apparent during the course of the following description.

In the drawings:

Figure 1 is a perspective view of a device embodying my invention.

Figure 2 is an end elevation of the same, the end member or plate being removed.

Figure 3 is a horizontal section taken on line 3—3 of Figure 2.

Figure 4 is a vertical section taken on line 4—4 of Figure 2.

Figure 5 is a perspective view of one of the operating elements.

Figure 6 is a central vertical longitudinal section through the device, parts broken away.

In the drawings, the numeral 10 designates a casing formed in companion casing sections, 11, the inner ends of which engage and have interlocking connection by means of a tongue and groove construction 12, or a plurality of such constructions. The assembled casing sections produce the casing 10 having a compressed tube receiving chamber 13 and a transverse web 14. Arranged upon the opposite side of the web 14 with respect to the chamber 13 is a forward chamber 15, having communication with a relatively large horizontal transverse opening 16, as shown. A reduced passage or slot 17 leads from the forward chamber 15 into the rear chamber 13, and this passage inclines downwardly in a rearward direction, as shown. The casing 10 includes ends 18, having outwardly laterally offset portions 19 and vertical passages 20 between the ends 18 and the offset portions 19.

Mounted within the chamber 15 is a pair of rollers 21 and 22, carried by shafts 23 and 24 respectively, and these shafts are journaled in openings formed in webs or lugs 25, integral with the offset casing portions 19 and disposed upon

the outer faces of the same. Secured to each end of the roller 21 is a gear 26, engaging a gear 27, secured to each end of the roller 22. These gears are rigidly secured to the rollers and are in mesh to cause the rollers to turn in opposite directions. These rollers are preferably knurled and slightly spaced.

The ends 18 are provided upon their outer faces with vertical grooves 28, and the web 14 has a longitudinal opening 29, receiving a rod 30, for clamping the casing sections 11 together, the ends of this rod or its head and nut, if any, carried thereby, being flush with the bottom of the grooves 28. Mounted to reciprocate within the grooves 28 are vertical operating bars or strips 31, Figure 5, having outwardly extending horizontal stops 32 and brackets 33. Arranged upon the outer faces of the bars 31 are vertically swinging pawls 34, having teeth 34' to engage with the gears 27. These pawls are pivoted to the bars 31 by pins 35, secured within openings 36. The pawls have tails 37, arranged to contact with the stops 32 and being disposed above these stops. The pawls are urged upwardly by springs 38, secured to the brackets 33, as shown.

The numeral 39 designates a vertical reciprocating plunger or bar, slidably within a transverse slot 40 formed in the top of the casing 10, and having pins 41 rigidly secured thereto, and these pins operate within vertical slots 42, formed in the ends 18, at the top of the grooves 28. The plunger or bar 39 is moved upwardly by compressible coil springs 43, engaging the top of the web 14. The pins 41 are held within openings 44, formed in the bars 31.

The numeral 45 designates generally flat end plates, which are removably mounted upon the ends 18. The end plates 45 are secured in position by screws 46, as shown. The end plates are provided near one end with recesses 47 to receive the bosses 48, and these bosses help to position the end plates 45. The end plates 45 are provided with inwardly projecting bosses 48, the inner surfaces 49 of which are disposed close to the outer surfaces of the pawls 34. The bosses 48 do not contact the pawls 34, but serve as means to prevent possible disengagement of the bars 31 and pawls 34 from the grooves 28.

The operation of the device is as follows:

A flexible tube containing plastic material has its flat end passed between the rollers 21 and 22. When it is desired to remove the paste, the cap is separated from the tube, and the plunger 39 is depressed. The teeth 34' are arranged to engage the teeth of the gears 27, and when the

plunger 39 is depressed the tails 37 engage the stops 32, and the pawls 34 will accordingly turn the lower roller 22. The rollers 21 and 22 have their adjacent faces turning in opposite directions, to feed the tube between them. When the plunger 39 is released, springs 43 return plunger 39 to the raised position, and pawls 34 then trip over the teeth of the gears 27. The springs 38 return the pawls 34 to the normal position, with their tails engaging stops 32, when the pawls disengage the lower gears 27. When this operation is repeated, the inner end of the tube is flattened and is fed through the passage 17 and is accumulated in the chamber 13.

When the flexible tube is empty and stored within the recess 13, and it is desired to remove the tube from the device, it is merely necessary to press down upon the bar 39 for its full travel, and the tube can be readily pulled out through the opening 16. The pawl 34, in its lowermost position, will have its teeth disengaged from the teeth of gear 27, and the rollers 21 and 22 can then reverse their movement as the empty tube is pulled out.

It is to be understood that the form of my invention herewith shown and described is to be taken as a preferred example of the same and that various changes in the shape, size, and arrangement of parts may be resorted to without departing from the spirit of my invention or the scope of the subjoined claims.

Having thus described my invention, I claim:

1. A device for squeezing and storing collapsible tubes comprising a hollow casing including a transverse partition subdividing said casing into spaced chambers, there being an opening provided in one end of said casing in communication with the adjacent one of said chambers for the insertion therethrough of a tube to be collapsed, a pair of rollers disposed in superimposed spaced relation with respect to each other and mounted within said one chamber for rotary movement about spaced transverse axes and adapted to receive said tube therebetween, an exteriorly actuatable plunger bar positioned intermediate said chambers and mounted contiguous to one side of said casing for movement toward and away from the other side thereof, resilient means operatively connected to said plunger bar for normally biasing the latter away from said other side of said casing, and means positioned within said casing and operatively connected to said pair of rollers and said plunger bar for rotating the former in response to the movement of the latter toward said other side of said casing, said partition being provided with a passage having its ends in communication with said chambers for the extension therethrough of said tube into the other of said chambers for storage therein.

2. A device for squeezing and storing collapsible tubes comprising a hollow casing including a transverse partition subdividing said casing into spaced chambers, there being an opening provided in one end of said casing in communication with the adjacent one of said chambers for the insertion therethrough of a tube to be collapsed, a pair of rollers disposed in superimposed spaced

relation with respect to each other and mounted within said one chamber for rotary movement about spaced transverse axes and adapted to receive said tube therebetween, an exteriorly actuatable plunger bar positioned intermediate said chambers and mounted contiguous to one side of said casing for movement toward and away from the other side thereof, resilient means operatively connected to said plunger bar for normally biasing the latter away from said other side of said casing, and means positioned within said casing and operatively connected to said pair of rollers and said plunger bar for rotating the former in response to the movement of the latter toward said other side of said casing, said partition being provided with a passage having its ends in communication with said chambers for the extension therethrough of said tube into the other of said chambers for storage therein, said last named means comprising gearing carried by said spaced axes for connecting said rollers together for movement in opposite directions with respect to each other, and pivoted spring biased pawls engaging said gearing and operatively connected to said plunger bar.

3. A device for squeezing and storing collapsible tubes comprising a hollow casing including a transverse partition subdividing said casing into spaced chambers, there being an opening provided in one end of said casing in communication with the adjacent one of said chambers for the insertion therethrough of a tube to be collapsed, a pair of rollers disposed in superimposed spaced relation with respect to each other and mounted within said one chamber for rotary movement about spaced transverse axes and adapted to receive said tube therebetween, an exteriorly actuatable plunger bar positioned intermediate said chambers and mounted contiguous to one side of said casing for movement toward and away from the other side thereof, resilient means operatively connected to said plunger bar for normally biasing the latter away from said other side of said casing, and means positioned within said casing and operatively connected to said pair of rollers and said plunger bar for rotating the former in response to the movement of the latter toward said other side of said casing, said partition being provided with a passage having its ends in communication with said chambers for the extension therethrough of said tube into the other of said chambers for storage therein, said casing comprising a pair of hollow sections disposed in face to face relation with respect to each other and detachably secured together.
